UNITED STATES PATENT OFFICE.

WALTER F. PALMER AND JOHN WINNACOTT, OF NEW YORK, N. Y.

PRESSWORK-RECORDER.

No. 830,923.

Specification of Letters Patent.

Patented Sept. 11, 1908.

Application filed July 7, 1905. Serial No. 268,674.

To all whom it may concern:

Be it known that we, WALTER F. PALMER and JOHN WINNACOTT, residents of the city of New York, borough of Brooklyn, in the county of Kings and State of New York, citizens of the United States, have invented a new and Improved Presswork-Recorder, of which the following is a full, clear, and exact description.

10 Our invention relates to a device for recording the work of a printing-press and machines of a similar character.

The principal objects of the invention are to provide means for showing the theoretical 15 number of papers produced and in connection therewith means for indicating when a web breaks.

Other objects of the invention will appear in the general description.

20 Reference is to be had to the accompanying drawings, forming a part of this specification, in which similar characters of reference indicate corresponding parts in all the figures.

Figure 1 is a diagrammatic view showing 25 in perspective portions of a printing-press, controlling means therefor, and a connecting system for these parts and our improvements. Fig. 2 is a front elevation with parts broken away, showing the recorder proper. 30 Fig. 3 is an end elevation of the same, and Fig. 4 is a plan.

In Fig. 1 we have shown a main solenoid which is provided with an armature 11, adapted to reciprocate in guides 12, having 35 divisions or steps thereon to show the position of the armature and to indicate the speed at which the press would theoretically be operated by power imparted to the press through one or more motors which are connected with the solenoid. For example, a ten-horse-power motor is connected with the solenoid and operates the press when the armature is on the first five steps at the top of the guides, means being provided for switching on a sixty-horse-power motor when the armature is opposite the other steps, it being understood, of course, that the power taken from the motor is less on the higher steps than on the lower. A small motor starts the 45 press on a worm-gear very slowly when the armature is on step one and increases the speed to the maximum on step five. At this point it is relieved by the large motor, which then runs the press on all higher speeds. The

solenoid 10 is termed the "brain" of this system of control. The armature is released and allowed to move downwardly by pushing a run-button at any of the button-boxes on the press. There may be twelve or more such boxes; but they are not shown, as they form no part of the present invention. This puts the current in a small solenoid behind the switchboard, the armature of the smaller solenoid releasing the armature of the large solenoid 10. This large armature, which goes down by gravity and may be regulated by an oil-dash inside the armature-core, if desired, may be let down a step at a time the entire distance, according to the length of time the button is held in. It is raised by pushing an "off" or stop button, which puts the current through the large solenoid 10 and pulls the armature 11 up against the resistance of the oil-dash and gravity. It is held at any point by the armature of the small solenoid, which is not shown. To avoid the heavy are that would occur at the button of such a large solenoid as 10, a relay-solenoid may be placed in that circuit. We connect this armature with a flexible connection in the form of a rope chain, or cable 13, passing over a pulley 14 and connected at one end with a pulley 15, fixedly mounted on a shaft 16. This shaft also carries another pulley 17, upon which is fixed the end of a certain flexible connection 18, similar to the first. This connection passes over guide-pulleys 19 to a sliding block 20, which is mounted on guides 21, shown in the present instance as being vertical. This block is shown as being provided with a passage 22, into which the connection 18 passes, and with a set-screw 23 for securing the connection at any desired point in the block and providing for adjustment to take up stretching in the connection due to usage. It is also provided with a rod 24, preferably formed of flexible or resilient material, upon which is carried a pen 25, adapted to contain ink and make a mark upon a cylinder 26. This cylinder is mounted on a shaft 27, which is provided with a projection 28 below the cylinder. Mounted at the end of the shaft and concentrically therewith is a clock 29 or similar motor having a disk 30, provided with one or more pins or projections 31, adapted to engage the projection 28 and rotate the cylinder. The cylinder is provided with spring-type

32 for securing a paper 33 upon its circumference. This paper is preferably of the usual type of cross-section paper used for making records. The operation of this part of the 5 device will be readily understood.

The cylinder being caused to rotate constantly at a given rate of speed, indicated by the cross-section paper, and the pen being filled with ink, the motions of the armature 11 10 will be transmitted to the pen, and the vertical position of the pen indicated on the paper by the lines formed by it will indicate the theoretical speed of the press and the number of papers which should be produced thereby. 15 The actual number of papers produced is recorded by a simple recording instrument, and by the comparison of the two records can be seen how much slip there is between the power and the printing parts of the press, thus showing any defect in the movement of 20 the press that would take more or less current than it should, as indicated by the readings on the chart. The marking element is controlled by the action of the solenoid feeding current to the press, and thus, although 25 not controlled by the actual speed of the press, it is indirectly used as a speed-indicator.

In order to indicate when the web breaks, a second solenoid 34 is provided. This solenoid is provided with an armature 35 and with contact-making devices 36 and 37, also with a projection 38, which is designed to engage a spring 39 to force it into contact with a second spring 40, placed adjacent thereto. 30 The springs 39 and 40 are designed to make contact with each other in order to connect two wires 41 and 42. The wire 42 is connected with a lever 43, pivotally mounted upon a stationary part of the machine. This lever is 35 provided with a long jaw 44 and a short jaw 45, separated by a notch 46, designed to receive a pin 47 upon a sliding block 48. This block acts as a journal for a roll 49 of the press and is forced upwardly by a spring 50. 40 The block and spring are duplicated on the two sides of the press, and the force of the spring is counteracted by the tension of the paper 51 upon the roll. When the paper breaks or is disconnected, this tension is released, and the springs are permitted to force 45 the blocks to the top of a pair of guides 52, in which they are mounted. This results in forcing the pin 47 into the notch 46 and tilting the lever 43 into such a position that its 50 projecting end 53 engages with a contact device 54, which is connected with a conductor 55. This conductor leads to an electromagnet 56, which controls the armature 57. This armature is pivotally mounted upon a 60 shaft 58 and carries a spring-arm 59, bearing a sharp-pointed pen 60.

When the magnet 56 is excited by the closing of the circuit in the conductors 41, 42, and 55, a sharp blow will be given to the paper on 65 the cylinder by the pen 60, this blow being

accelerated by a weight 61, mounted on the arm 59.

The position of the pen 60 is normally out of contact with the paper, and the operation of it is such as to puncture the paper and then to fly back to a short distance from it, so that the point of the pen will not interfere with the rotation of the disk and the paper. The pen may be adjusted by a set-screw 62. The circuit for operating these devices is completed after it passes through the magnet 56 by a conductor 63, connected with the magnet and with a spring 64. This spring normally bears upon an insulating-bar 65, mounted on the block 20. When this block is down, it 70 keeps the end of the spring away from a contact-piece 66, which is directly connected with the conductor 41; but when the block is raised the spring 64 is allowed to move into the normal position, so as to make the contact at this point and permit the circuit to be closed. This electric circuit is provided with batteries or other means for generating a current. The operation of this part of the device is as follows: When the block 20 is in depressed position, owing to the fact that the solenoid 10 is at the top of its stroke and no motion is imparted to the press, this electric circuit cannot be completed by any manipulation of the other parts, and the paper may 75 be removed from the machine or broken at will without causing the pen 60 to puncture the paper. Also when the solenoid 34 is in such condition that the contact-piece 38 will not press the spring 39 against the spring 40 80 the circuit is open at this point and the paper may then be broken, although the machine is in operation, without puncturing the paper. This may be provided for by operating by 85 hand a switch in the magnet-circuit, and it is desired because it is necessary to change the web at times, and it is not desired to record any breaking of the web against the paper when it is disconnected intentionally. If, however, the two contacts at the points 40 90 and 66 are closed, as is the case when the machine is running in its natural way, the breaking of the web will cause the pin 47 to operate the lever 43 and close the circuit at the point 54. The puncture of the paper in this 95 manner will record not only the number of breaks in the web, but the times at which these breaks occur, as will be readily understood from the previous description of the operation of the cylinder regarding the recording-paper.

We have shown the main parts of the work-recorder as mounted upon a bracket 67, which is preferably located at some distance to the rear of the switchboard which supports the solenoids 10 and 34, together with the usual solenoids which are ordinarily employed in operating presses of a similar character.

Having thus described our invention, we 130

claim as new and desire to secure by Letters Patent—

1. The combination in a work-recorder of means for supporting a recording - sheet, means for moving said sheet at a uniform

5 rate of speed, means for making a mark on the sheet to indicate the theoretical speed of a press, and means for recording on the same sheet, breaks in the web passing through the press.

10 2. The combination with a main solenoid having an armature, of a sliding block, means for connecting the armature with the block to transmit motion from one to the other, a guide for said sliding block and a

15 marking device connected with the block, said block being provided with means for adjusting the connection between it and the armature, a second solenoid, an electric circuit having a contact device, means connected with the second solenoid for controlling said contact device, means connected with

20 said block for breaking said circuit, and means in said circuit for causing a record to be made when the circuit is closed.

25 3. The combination with a controlling-solenoid having an armature and a second solenoid having an armature, of a recording device connected with the first solenoid, an

30 electric circuit adapted to be closed by the second solenoid, means connected with said recording device for opening said electric circuit, an electromagnet in said circuit, and a second recording device controlled by said magnet.

35 4. The combination with a solenoid, of an electric circuit having a contact device which is normally open, means connected with said solenoid for closing the contact, an electromagnet in the circuit, a pivoted armature controlled by said electromagnet, a resilient arm on said armature, a weight on the arm and a recording element mounted adjacent to said weight.

40 5. The combination with an electric circuit, of a normally open contact device therefor, means for closing said contact device, an electromagnet in the circuit, a movable armature controlled by said magnet, a

45 resilient arm connected with the armature, a weight on the arm, a recording element mounted adjacent to the weight, and means for receiving a record from said recording element located in such position that the recording element is normally out of contact with it whereby the excitation of said magnet will cause the weight to force the pen against the means for receiving the record, and the resiliency of said arm will then force the recording device away from said means.

50 6. The combination of a roll for receiving a web under tension, a resilient means for forcing said roll against the web in a direction contrary to the tension on the web, an

55 electric circuit, a recording device connected

with said circuit, and means for closing the circuit when the tension is removed from the web and the said resilient means is allowed to act.

7. In a recording device, the combination 70 of a movable element adapted to receive a web under tension, resilient means for forcing said element toward the web, a lever, means connected with said movable element for moving said lever, a contact device 75 located in the path of movement of said lever for closing an electric circuit, and means operable upon the closing of said circuit for making a record.

8. In a recording device the combination 80 of a roll adapted to receive a web, resilient means for forcing said roll toward the web, a projection connected with said roll, a lever adapted to receive said projection and to be moved thereby when the roll moves, a contact device adapted to be engaged by said lever when so moved, an electric circuit having an open contact device connected with said first-mentioned contact device and with said lever, additional means for closing said 90 electric circuit, a recording instrument, and means in said circuit for controlling said recording instrument.

9. A recording device comprising a movable element having a projection, means for 95 moving said element, a lever having two arms separated by a space, both arms being adapted to engage said projection and the space being located in position for receiving the projection when said member moves to extreme position, an electric circuit, a recording device controlled by said circuit, and a contact in the circuit adapted to be closed by said lever when the projection engages one arm thereof.

10. A recording device, comprising a movable element having a projection, means for moving said element, a lever having a long and a short arm separated by a space, the short arm being located on the side of the lever toward said projection and the space being located in position for receiving the projection when said member moves to extreme position, an electric circuit, a recording device controlled by said circuit, and a 115 contact member adapted to be closed by said lever when the projection engages the long arm thereof.

11. The combination with a controlling-solenoid and a second solenoid, of a recording device connected with the first solenoid, an electric circuit adapted to be closed by the second solenoid, means connected with said recording device for opening said circuit, and a second recording device controlled by the circuit.

12. The combination with a main solenoid having an armature, of a movable block, means for connecting the armature with the block to transmit motion from the latter to

the former, a second solenoid, an electric circuit having a contact device, means connected with the second solenoid for controlling said contact device, means connected with said block for breaking the circuit, and means in the circuit for causing a record to be made when the circuit is closed.

13. The combination with a main solenoid having an armature, of a block, means for connecting the armature with the block to transmit motion from one to the other, an electric circuit, means connected with said

block for breaking said circuit, a recording device in said circuit, and means for causing said device to operate when the circuit is closed.

In testimony whereof we have signed our names to this specification in the presence of two subscribing witnesses.
